UNITED STATES PATENT OFFICE.

ARMAND PEUGEOT, TONY HUBER, AND HENRI DE LOSTALOT, OF BILLANCOURT, FRANCE.

EXPLOSION-MOTOR.

No. 886,539.

Specification of Letters Patent.

Patented May 5, 1908.

Application filed May 6, 1907. Serial No. 372,259.

To all whom it may concern:

Be it known that we, ARMAND PEUGEOT, TONY HUBER, and HENRI DE LOSTALOT, civil engineers, citizens of France, residing at 56 5 Rue du Vieux Pont de Sèvres, Billancourt, Seine, France, have invented new and useful Improvements in Explosion-Motors, of which the following is a specification.

This invention relates to improvements in 10 explosion motors.

The improved explosion motor of this invention is of two-stroke cycle, wherein by the combination of a special piston and a form of sliding shutter for the cylinder, an exceptional lightness is secured to the motor, together with increased action.

The improved motor is preferably provided with a suction valve of particular construction, which allows the weight of the 20 whole to be lessened still further in comparison with the weight of known motors.

On the annexed drawing Figure 1 is a longitudinal section of the motor, through the axis of the cylinder. Fig. 2 is a view from 25 below of the cylinder showing the arrangement of the sliding shutter. Fig. 3 is a section and Figs. 4 and 5 elevations with parts broken away showing the construction of suction valve.

30 In the improved motor, the hollow piston A as well as the case A' which lengthens the same are constructed of aluminium or of a light aluminium alloy and the bottom of the cylinder at the side of the connecting rod B, 35 instead of opening as usual into a crank inclosing chamber is closed immediately above the point where the piston stops at its lowest position by a sliding shutter which assures the tight closing of the cylinder while allowing the oscillating connecting rod B to work 40 freely.

This sliding shutter consists of a thin, sliding plate f of a convenient length, carrying centrally a socket joint g h, in order to allow 45 the piston rod to pass through at the same time forming a joint round the same, this plate being moved by the lateral reciprocating movement of the connecting rod and sliding on the smooth upper surface of the cylinder bottom said bottom being attached and 50 screwed on at b. Mortised grooves provided in the sides of the said cylinder form guides for the sliding plate in such a manner as to close constantly in a tight manner the longi-

tudinal opening c provided in the bottom of 55 the cylinder. By this means the oscillating connecting rod can reciprocate freely.

The action is as follows: When the piston A A' arrives at the bottom of its stroke after an explosion (position of Fig. 1) the burned 60 gases escape after expansion through the orifice j pierced in the side of the cylinder C; at the same time the fresh explosive gases compressed between the piston and the bottom 65 with sliding shutter escape by the conduit k, follow round the piston and partition guide l and accumulate towards the outlet operating to drive out the burned gases. Continuing its course, the piston, in rising, shuts off the two escape and admission orifices j and k 70 provided in the cylinder and compresses towards the outlet the fresh gases, which will explode near the dead point; the other face of the piston acting as a suction pump draws in through the pipe x and admission 75 valve either petrol, gas or other combustible products together with air, the air and gas being either previously mixed in a carburetor, or separate. The admission valve closed the pipe x at the moment of the subsequent compression necessary for the transport of the 80 fresh gases towards the outlet.

In its descent the piston receives the motive force from the explosion and compresses 85 by its other face as has been above described.

By the combined use of a piston of aluminium or alloy of aluminium and of the sliding shutter of the cylinder, the weight of the motor is considerably lessened the aluminium 90 weighing much less than the ordinary casting and the crank chambers or an additional pump by which the aspiration is done being dispensed with. Also, the vibrations due to the inertia of the piston are considerably 95 lessened. Besides the above the following important results are obtained.

Aluminium, even in a state of alloy, conducts heat much better than the ordinary casting. The upper face of the piston in 100 motors of two-stroke cycle becomes greatly heated owing to the flow of escaping gases; in our invention this heat spreads very quickly in the chamber A' of the piston said piston acting as a large cooling plate thereto; this plate which plunges in the fresh gases coming between the piston and the bottom 105 with sliding shutter, gives its heat to these

gases and heats them before their compression, by which means the working and the power of the motor is improved.

The lightness and the efficient working of the motor can be further increased by the use of the admission valve represented in Fig. 1 and in Figs. 3, 4 and 5. This valve is formed of a reversed V plate *m*, provided with large openings *n* which are closed or opened by the oscillation of very thin steel plates *o*, flexible round their points of connection. These thin steel plates have over the ordinary valves of explosion motors the advantage of extraordinary lightness of weight (3 to 4 grams to a cylinder for a motor of 10 to 15 horse power); on account of this lightness of weight and their elasticity the improved valve acts in perfect accordance with the sucking of the motor, which sensibly increases the power of the same especially for rapid rotation of 1500 revolutions or more at which speed inertia of the valve would have considerable effect.

Our improved valves with plates of a thickness of a tenth and a half to three tenths of millimeter, re-act very well against pressures of 8 to 10 kilos, without permanent deformation. They have further the advantage of conducting the gases without serious power loss.

Having now described our invention, what we claim as new and desire to secure by Letters Patent is:

An explosion motor of two-stroke cycle comprising in combination a cylinder *C*, a widened portion formed at the lower end of said cylinder, an opening formed in the widened portion of the cylinder, an admission opening *k* formed in the middle-part of the cylinder, a conduit connecting the said opening, a third opening *j* formed in the cylinder for the escape of the gases, a sliding cover *b* *f* closing the cylinder immediately above the point where the piston stops, a hollow piston *A*, an extension *A'* formed on the piston adapted to be surrounded and consequently cooled by the admission gases, and an admission valve arranged just opposite the opening formed in the widened portion of the cylinder, substantially as described and for the purpose set forth.

In testimony whereof we have signed our names to this specification in the presence of two subscribing witnesses.

ARMAND PEUGEOT.
TONY HUBER.
HENRI DE LOSTALOT.
